UNITED STATES PATENT OFFICE.

WILHELM BECKER, OF NEW YORK, N. Y.

DESIGN FOR A WATCHCASE.

Application filed March 21, 1927. Serial No. 21,228. Term of patent 3½ years.

Whom it may concern:

Known that I, WILHELM BECKER, a
of Germany, residing at New York, County of New York and State of York, have invented a new, original, amental Design for Watchcases, of he following is a specification, refer-ng had to the accompanying draw-ming part thereof.

Figure 1, is a face view of a watch case,
my new design.

Figure 2, is a perspective view of my new design with the face ornamentation shown in Figure 1 omitted, for the purpose, of showing contour.

I claim:

The ornamental design for a watchcase,
as shown, and described.

WILHELM BECKER.
